UNITED STATES PATENT OFFICE.

PETER S. SIMMONS AND WILLIAM J. FRICK, OF PATERSON, NEW JERSEY.

FOLDING UMBRELLA.

1,396,893.

Specification of Letters Patent.

Patented Nov. 15, 1921.

Application filed February 21, 1920. Serial No. 360,296.

To all whom it may concern:

Be it known that we, PETER S. SIMMONS and WILLIAM J. FRICK, citizens of the United States, residing at Paterson, in the county of Passaic and State of New Jersey, have invented certain new and useful Improvements in Folding Umbrellas, of which the following is a specification.

This invention relates to folding umbrellas, and particularly to folding umbrellas of the class in which the ribs are composed of pivotally connected sections. Instead of arranging the outer section of each rib to move pivotally in the same radial plane as the inner section, which results at the joint in forming a step, projection or other breech of continuity in the outer or fabric-supporting surface of the rib that reveals itself through the fabric when the umbrella is raised and causes the fabric to wear away at that point, we arrange the outer section to move pivotally in another radial plane, that is, in a plane beside that of the inner section. Preferably the pivot for the outer section is arranged somewhat short of the free end of the inner section, and the latter has a lateral stop or rest against which the outer section bears when the ribs are extended.

In the drawing,
30 Figure 1 is a side elevation of the improved folding umbrella frame, raised;
Fig. 2 is a side elevation of a fragment of one of the folding ribs including the joint portion;
35 Fig. 3 is a plan of what is shown in Fig. 2; Figs. 4, 5, 6 and 7 are sectional views on lines 4-4, 5-5, 6-6 and 7-7 of Fig. 3; and

40 Figs. 8 and 9 are plan views of blanks for certain parts.

a indicates the staff which is preferably in a plurality of parts suitably connected together at *b*, the manner of connection not being material to the present invention; *c* is the crown; *d* the runner and *d'* the upper and lower catches therefor; and *e* the stretchers.

Each inner rib section *f*, pivoted to the crown *c* and formed preferably of channeled material such as is commonly used for umbrella ribs, has secured to its free end a saddle-piece *g* the blank for forming which is illustrated in Fig. 8 as having on one side projections *g'*, *g²* and *g³* and on the other side complementary projections *g'*, *g²* and *h*,

the projection *h* being somewhat longer than its complement *g³*; the intermediate projections are preferably rounded and they have holes *i*. The saddle-piece is attached to the end of the section *f* by bending it on a line between the two sets of projections so as to fit over the section and then bending the projections *g'*, *g³* on one side and *g'* on the other up into the channel of said section, the projections thus serving to clench the saddle-piece in place. The two intermediate projections are left in a pendent relation, while the projection *h* is bent laterally and back to form a hook-shaped rest or seat. The holes *i* receive a pin *j* which forms the pivot for the end of the stretcher *e*, which is received between the two wings or projections *g²*.

Another saddle-piece *k* is secured to the inner section. The blank for this saddle-piece is shown in Fig. 9 as having on one side two end or narrow projections *k'* and one intermediate or wide projection or elongated edge-portion *k²*. This saddle-piece is attached to the inner rib section *f*, inwardly of the saddle-piece *g*, by bending it on a line between the said projections and the opposite side or edge thereof so as to fit over the section *f* and then bending the projections *k'* and the said opposite edge portion *k²* up into the channel of section *f* so that they serve to clench the saddle-piece in place. The intermediate projection *k²* is bent laterally and back to form a channeled portion whose channel opens oppositely to the channel of the section *f*. A pin *l* penetrates the saddle-piece and contained portion of section *f*, being parallel to the pin *j*.

The outer rib section *m* is also preferably formed of channeled material the same as the inner rib section *f*, and it has its inner end flattened, as at *n*, and fairly snugly received in the channel of saddle-piece *k*, being pivoted on the pin *l*. When the rib is extended, the outer section *m* thereof obtains support on the seat or rest *h*, which engages up in the channel of said section and thus prevents any lateral play, see Fig. 7.

The opening and closing of the umbrella occur the same as in any ordinary umbrella. But by releasing the upper catch *d'* the runner *d* may be run up to the crown *c*, so that the stretchers are grouped around the upper portion of the staff *a* (dotted lines, Fig. 1) and the ribs may be collapsed or closed, in

which position their outer sections may now be folded outwardly and back on their upper or inner sections *f*.

By arranging the outer section so that it is pivotally movable in a plane beside that of the inner section of each rib we produce a joint between the sections that avoids unduly prominent steps, projections or the like on the fabric-supporting surface of the rib and also the pinching of the fabric by the rib when the latter is folded.

The coacting means to limit the movement of the outer rib sections past the position where they will be alined with the inner rib sections form an interlock (as indicated in Fig. 7, by portion *h* engaging in the channel of rib section *m*), that preserves the sections parallel in plan when the ribs are extended.

Having thus fully described our invention, we claim:

1. A folding umbrella rib including an inner member and an outer member pivoted on the inner member and pivotally movable in a plane beside that of the inner member, one member having at a point removed from

the pivot between said members a lateral hook and the other at a point correspondingly removed from said pivot a channel adapted to receive said hook and coact with the hook to limit the pivotal movement of the outer member.

2. A folding umbrella rib including an outer and an inner section, the outer section being pivotally movable in a plane beside the inner section and one section being channeled, a sheet-metal piece bent around the convex side, and having opposite edge portions thereof bent into the channel, of the channeled section and also having a lateral elongated edge portion thereof rebent into a channeled portion, said channel-portion snugly receiving and its opposite walls laterally supporting the other section, and a pivot penetrating both said walls of the channel-portion and also penetrating the other section.

In testimony whereof we affix our signatures.

PETER S. SIMMONS.
WILLIAM J. FRICK.
